(57) **CLAIM**

The ornamental design for a hammer with notched pick, as shown and described.

DESCRIPTION

FIG. 1 is a left side elevational view of a hammer with notched pick showing my new design. The right side elevational view being a mirror image.

FIG. 2 is a rear orthographic view of the hammer and notched pick thereof;

FIG. 3 is a top plan view thereof;

FIG. 4 is a bottom plan view thereof;

FIG. 5 is a front elevational view thereof; and,

FIG. 6 is a rear elevational view thereof.

The broken lines in FIG. 1 illustrate environment that forms no part of the claim.
